DESIGN FOR A COMB HOLDER

William T. Collins, Lillington, N. C.

Application January 6, 1949, Serial No. 84

Term of patent 7 years

(Cl. D86—10)

To all whom it may concern:

Be it known that I, William T. Collins, a citizen of the United States of America, residing at Lillington, in the county of Harnett, in the State of North Carolina, have invented a new, original, and ornamental Design for a Comb Holder, of which the following is a specification, reference being had to the accompanying drawings, forming a part thereof.

I claim:

The ornamental design for a comb holder, substantially as shown.

WILLIAM T. COLLINS.
